UNITED STATES PATENT OFFICE.

JOHN H. HUNT, OF DETROIT, MICHIGAN, ASSIGNOR TO DELCO-REMY CORPORATION,
OF DAYTON, OHIO, A CORPORATION OF DELAWARE.

LIGHTING AND IGNITION SYSTEM.

Original application filed October 25, 1924, Serial No. 745,942. Divided and this application filed
March 21, 1927. Serial No. 177,020.

This invention relates to electrical systems for automotive vehicles and particularly to apparatus for applying ignition current for the engine and current for lighting purposes. 5 This application is a division of my co-pending application Serial No. 745,942 filed October 25, 1924.

This invention is particularly adapted for use on farm tractors and the like which do not generally require electrical starting apparatus and, consequently, in which the storage battery is not necessary.

In electrical systems which supply current for engine ignition and vehicle lighting only, 15 there is usually provided one dynamo-electric machine, a magneto, which furnishes current for ignition purposes, and a separate dynamo-electric machine is provided for furnishing the vehicle with electric lighting. Sometimes 20 the two machines are combined all in one unit, but such a machine has separate fields and separate armatures so that the unitary structure is in effect two separate dynamo-electric machines. Precautions are sometimes 25 taken to insulate magnetically the two fields from one another so that the operation of one dynamo-electric machine may not affect the operation of one other in the unitary structure. Where magnetos are used to supply 30 ignition current for engines which are started by hand, it has been found necessary to use impulse starters so that the magneto may be operated with sufficient rapidity periodically, to supply ignition current while the engine 35 is being cranked by hand.

It is among the objects of the present invention to provide a lighting and ignition system including a dynamo-electric machine having a permanent magnet field and one 40 rotor for supplying current both for ignition and for lighting purposes.

It is a further object to provide electrical apparatus for supplying current sufficient for ignition purposes at engine speeds attained 45 by cranking and without the use of an impulse starter drive or coupling between the magneto and some engine part operated by the hand crank.

A further object is to provide a system of 50 regulation wherein the potential of the lighting current will remain substantially constant over a wide variation of engine speed. In this connection it is an object to provide

regulating circuits in which no moving parts are required.

A further object is to provide a system of control wherein the supplying of ignition by the dynamo-electric-machine does not appreciably interfere with the supplying of lighting current.

Other and further objects of the present invention will be apparent from the following description, reference being had to the accompanying drawings, wherein a preferred form of embodiment of the present invention 65 is clearly shown.

In the drawings:

The figure of the drawing is a wiring diagram illustrating the invention.

The generator 30 for supplying the lighting and ignition circuits of the present invention is disclosed in detail in my co-pending application, Serial No. 576,493, filed October 25, 1924. For understanding the present invention it is sufficient to state that the generator 30 includes a stationary two-pole permanent magnet field 31 the poles 33 and 34 of which are laminated and each provided with preferably four teeth spaced by slots for receiving pole face windings. The eight pole teeth (numbered 41 to 48 inclusive) extend 70 radially with respect to the armature axis, and are equally spaced.

The dynamo 30 includes an armature 84 which is carried by a shaft 76 which is operated by an internal combustion engine 20 at twice engine speed through gears 21 and 22.

The armature core 84 is laminated and the cylindrical periphery thereof is notched to provide a series of equally spaced teeth 220, 90 the face of each tooth being approximately one-third the greatest width of the notch between adjacent teeth. It is desirable that the notches spacing the teeth be as wide as possible in order to reduce flux leakage to the minimum. But on the other hand, if the notches are too wide, the teeth 220 will be too narrow to carry efficiently the flux from the various pole teeth of the permanent magnets. Satisfactory proportions of width of notch to width of armature tooth face have been found to be from 4/1 to 2.5/1. The notches between certain of the armature teeth 220^a, 220^b, 220^c, 220^d, 220^e, and 220^f, are made considerably deeper 100 than other notches in order to provide for the 105

armature winding, arranged in two coils 221 and 222 which are wound about armature core 84 after the fashion of the ordinary shuttle wound armature windings, and these windings are connected in series and one end of the group of windings is grounded by a grounded brush 201, and the other end of the group of armature windings is connected by a brush 160 and wire 161 with a timer mechanism and an ignition coil to be described. By way of example, the following armature dimensions are given to show what proportions having been found satisfactory in one machine constructed in accordance with the present invention: Core length 3 inches. Core diameter 1.875 inches. Twelve core teeth. Windings 221 and 222 have each 100 turns of No. 23 wire. It will be noted that the magnetic armature windings differ from the ordinary shuttle wound armature windings in that the windings include two coils which are separated by the relatively long armature core teeth 220^b and 220^c. This construction increases the time of duration of the short circuit current in the armature at values continuously above the minimum required for ignition and also reduces the inductance per turn to a value substantially less than what it would be if the windings were concentrated. This arrangement permits a wider range of adjustment of the ignition timer than is possible where the armature turns are all concentrated between adjacent core teeth.

The pole face windings 231, 232, 233, 234, 235, 236, 237, 238 surround the field pole teeth 41 to 48 inclusive, respectively; and, when joined in series their E. M. F.'s are cumulative. These windings supply current to the headlamps 291 and 293. Current for the tail lamp 317 is induced in pole face windings 243 and 244 which surround diametrically opposite field pole teeth 41 and 45 and are connected so that their E. M. F.'s are cumulative. One example of satisfactory field pole coil dimensions is given for an armature core having a length of 3 inches, and a diameter of 1 $\frac{7}{8}$ inches: winding 232, 233, 234, 236, 237 and 238 each have 40 turns of No. 17 wire. Windings 231 and 235 each have 30 turns of No. 17 wire. Windings 243 and 244 each have 150 turns of No. 27 wire.

An extension 76^a of the armature shaft 76 carries a timer cam 78 which cooperates with the rubbing blocks 152 and 156 of breaker levers 149 and 154 respectively carrying timer contacts 147 and 148 respectively which engage contacts 145 and 146, respectively. Springs 151 and 158 cooperate with the levers 149 and 154, respectively, to urge the levers 60 toward the cam 78. Numeral 65 indicates a suitable timer housing or cup which is secured to the dynamo frame in any well known manner. The shaft 76^a carries a gear 181 meshing with a gear 183 which operates a shaft 182 carrying a distributor rotor con-

tact 185 which distributes sparking impulses from a center terminal 194 to terminals 192 supported by a distributor head 189. Terminals 192 are connected with engine spark plugs 256. The ratio of gears 181 and 183 is four to one so that the rotor 185 will rotate at one-half engine speed.

The wire 161 connects the armature coils 221 and 222 with the lever 154 which is insulated. Wire 140 connects the contact 146 with contact 145. Contacts 148, 146, and 145 are insulated, and contact 147 is grounded since the lever 149 is grounded upon the timer cup 65. A condenser 250 is connected in shunt with contacts 146 and 148, and a condenser 251 is connected in shunt with contacts 145 and 147.

A wire 170 connects the wire 140 with the primary 253 of an ignition coil 252. The secondary 255 is grounded with coil 253 at 254, and is connected by wire 256 with the rotor contact 185.

In the drawing, an ignition switch 260 includes a switch lever 261 carrying contacts 262 and 263 which are insulated from one another. Contact 263 is connected with the pivot point of the lever 261 which is grounded at 264, and contact 263 is arranged to engage stationary contacts 265, 266, or 267. Contact 262 is arranged to connect two stationary contacts 268 and 269. Contacts 269 and 265 are joined by wire 270; contact 268 is joined with magneto terminal 239 by wire 271; stationary contact 265 is connected with wire 161; contact 266 is connected by wire 272 with magneto terminal 242; and contact 267 is connected by wire 273 with magneto terminal 240.

The externally regulated lighting circuits include, respectively, the group of pole face windings 231 to 234 inclusive, having a terminal 239, and the group of pole face windings 235 to 238 inclusive having a terminal 240. These groups of windings have a common ground terminal 242. The terminal 239 is connected by wire 280 with a transformer primary 281 which is connected with a switch blade 282 adapted to engage with contact 283 or to connect contacts 284 and 285. Terminal 240 is connected by wire 286 with a transformer primary 287 which is connected with a switch blade 288 adapted to engage contact 289 or 290. Contacts 283 and 285 are connected with an electric lamp 291 grounded at 292 and contacts 289 and 290 are connected with an electric lamp 293 grounded at 294. Contacts 284 and 289 are connected together through a dimmer resistance 295. The transformer primaries 281 and 287 cooperate with transformer secondary windings 296 and 297 which are connected together in series with a condenser 298. Preferably the windings 296 and 297 are grouped together on one leg of a magnetic circuit while the windings 281 and 287

are mounted upon another portion of the same magnetic circuit.

In the drawing the lever 261 is shown in RUN position, but to start the engine this lever 261 is moved into the START position so that the contact 262 will engage contacts 268 and 269 and the contact 263 will engage the contact 267. The pole face windings are now connected in series and altogether in parallel with the magneto armature windings 221 and 222 so as to assist in producing a sparking impulse sufficient for engine ignition even when the engine is cranked by hand and the magneto armature rotates at a relatively slow speed. The pole face windings are connected up in the following manner with the wire 161; ground 264, switch contact 263, contact 267, wire 273, terminal 240, windings 238 to 231, terminal 239, wire 271, contacts 268, 262, 269, wire 270, contact 265 which is connected to the wire 161.

The current wave of the pole face windings includes a series of peaks alternating above and below the zero line. In the machine disclosed, during a revolution of the armature, there will be twelve positive peaks alternating with twelve negative peaks, and the peaks will extend approximately the same distance from the zero line.

The current wave of the armature, when short-circuited also includes a series of peaks extending alternately above and below a certain mean line. This mean line is not the zero current line but approximates a sine curve making a complete wave each revolution of the armature. During each revolution of the armature of the machine disclosed there will be twelve peaks in the armature current above this mean line alternating with twelve peaks below the mean line. Once a revolution there is a peak extending above the mean line which has a positive value greater than any other of the positive peaks in the armature short-circuit current wave, and it happens that this peak occurs substantially in phase with one of the positive peaks of the pole face winding current wave.

This coincidence of these particular current wave peaks is taken advantage of in providing ignition current during slow cranking of the engine. When the pole face windings are connected in parallel with the armature windings in the manner stated, these two peaks are added to produce a peak every armature revolution having a current value sufficient for ignition purposes at engine speeds produced by hand cranking. After the engine has become self-operative these maximum positive peaks of the armature current will alone be sufficient for ignition purposes, and half way between maximum positive peaks, there will be a maximum negative peak sufficient for engine sparking. Therefore, during each armature revolution during normal engine running there will be at least two

instants when sufficient current is available for ignition.

The arrangement of the ignition timer depends on the ratio of magneto speed to engine speed. Where the dimensions of the magneto are limited by space requirements, it may be necessary to operate the magneto at speeds greater than engine speed in order to provide sufficient output for lighting purposes. Although the magneto disclosed is constructed to be operated at twice engine speed, the invention is not thus limited, but includes magnetos operable at other speeds such as one operating at engine speed.

When a magneto of the character described operates at twice engine speed it is necessary to provide a special breaker mechanism, which, during the normal running of the engine, will permit the use of, only the maximum positive peaks or the maximum negative peaks of the armature current wave so that there will be one sparking impulse for each magneto revolution. This will give four impulses for each engine cycle, sufficient for a four cylinder engine. If it is the maximum positive peaks of the armature current wave which assist the pole face current in providing starting ignition the timer is constructed to use only the maximum positive peaks during starting and running of the engine.

The cam which operates the breaker levers for controlling the pair of contacts 145, 147 and the pair of contacts 146, 148 is provided with two flats located preferably at 150° apart and the breaker levers have their respective cam rubbing blocks similarly placed. Each breaker lever closes and opens twice a magneto revolution, but only once a revolution are both breaker levers closed at the same time. The drawing shows the cam 78 in position for opening the lever 154 after lever 149 has opened. The cam 78 rotates clockwise as viewed in the drawing. For example, the home or zero position of the cam may be the instant of opening lever 149. Lever 154 will open at about 15° of cam rotation beyond home position and will close at about 125° and then open at 165°. Lever 149 will close at about 170° and open at about 210° and will close again at about 320°. At about 335° lever 154 will close. Thus, between 335° and 360° both levers will be closed to complete the short circuit of the armature coils 221 and 222 once each revolution of the magneto and four times for each cycle of the four-stroke cycle four cylinder engine 20. The lever 149 opens substantially at the instant of the maximum positive armature short-circuit current peak, in order that a sparking impulse will be produced in the coil 252. The distributor contact 185 will conduct this impulse to one of the engine spark plugs 253. The armature coils will remain open circuited from 15° to about 125° and from 165° to 335°. It is desirable to keep the armature

windings open circuited as long as possible because the short circuiting of the armature has a demagnetizing effect on the permanent magnets.

- 5 The closing of the breaker lever 154 at 125° of magnet rotation from home position will connect the transformer coil 252 with the magneto armature coils 221 and 222, and the opening of the breaker lever 154 at 165° 10 will open-circuit the armature coils. Although a sparking impulse may be generated by the opening of the lever 154 at 165°, no ignition will then be supplied to the engine since the distributing rotor is about midway 15 between the distributor contacts 192. The closing and opening of the breaker lever 149 at 170° and 210°, respectively, will have no effect since the lever 154 is then open. The lever 149 is closed at 320° from home position 20 in order that, when the lever 154 closes at 335° the short-circuit of the armature coils will then be completed. As stated before, when the lever 149 opens at the end of the magneto cycle or at 360° from home position, 25 a sparking impulse will be produced in the transformer coil 252. The opening of the lever 154 at 15° following the opening of the lever 149 causes the armature circuit to be interrupted as soon as practicable after the 30 sparking impulse has been generated.

After the engine becomes self-operative the speed of the magneto will be such that the value of the maximum positive peak of the armature current wave will be sufficient for 35 ignition purposes. The wave form for the pole face winding current will remain substantially the same but the height of the peaks will tend to increase with increasing engine speed. Regulation of the lighting circuit however is effected in a manner to be described.

If, for example, the magneto be one constructed to operate at engine speed, and fire a four cylinder engine exploding at equal intervals, then the timer would be constructed to use the maximum positive peak and maximum negative peak every magneto revolution so that there would be four sparking impulses for each engine cycle for a four-stroke 45 cycle engine. The timer cam would have the flats located 180° apart and the breaker levers arranged so that twice a revolution both levers would be closed at the same time. The levers would be arranged so that the grounded breaker 149 would open slightly ahead of the breaker 154 in order to maintain the armature open circuited as long as possible.

It is to be understood also that the present 50 invention is not limited to ignition for a four cylinder four-stroke-cycle engine, but can be applied to ignition for other multicylinder engines with such changes as will be apparent to those skilled in the art.

The dividing of the armature windings 55 into two coils 221 and 222 separated by core

teeth results in the maximum positive armature current peaks being of such a shape that for a relatively great proportion of the duration of the wave peak, the peak is at values greater than the minimum required for ignition purposes. Therefore, although the breaker lever rubbing block may wear into a different shape and tend to change the ignition timing, a certain variation is permissible because of the character of the wave peak just 75 described.

After the engine has become self-operative the lever 261 is moved into RUN position shown in the drawing. If the levers 282 and 288 are in BRT (bright) position in the 80 drawing, one of the externally regulated circuits will be as follows: ground 264, switch 263, contact 266, wire 272, terminal 242, pole face windings 234, 233, 232, and 231, terminal 239, wire 280, transformer primary 281, lever 85 282, contact 283, lamp 291, and ground 292. The other externally regulated circuit will be as follows: ground 264, switch 263, contact 266, wire 272, terminal 242, pole face windings 235, 236, 237 and 238 terminal 240, 90 wire 286, transformer primary 287, lever 288, contact 290, lamp 293 and ground 294. The coils 231 to 238 which were connected together in series to serve as an ignition booster circuit are now divided into two groups by the common grounding terminal 242, namely, group of coils 231 to 234, inclusive, for supplying current to lamp 291, and group of coils 235 to 238, inclusive, for supplying current to lamp 293.

The function of the circuits including the transformer windings 281, 296 and 287, 297, and the condenser 298 is to regulate the voltage of the lighting circuits. This is explained in detail in my copending application Serial No. 745,942.

To stop the engine, lever 261 is moved to STOP position wherein the contact 263 engages contact 265 and the armature is short circuited.

The following advantages are present in this invention:

The generating unit provides current for lighting and current for ignition by the use of but one magnetic circuit and source of 115 magnetism and one set of rotating windings. The magnets and armature cooperate to provide ignition current, and pole face windings and the armature teeth or inductor poles cooperate as a high frequency A. C. generator 120 to produce lighting current.

In high frequency A. C. machines, it has been the practice to employ more stator slots than inductor poles, but such practice could not be employed in the present invention as the winding space would be insufficient. Also the available flux is limited where permanent magnets are used. In the large inductor alternator more flux is available in proportion than in a small magneto because the field 130

is separately excited and the iron is worked much harder. But in a magneto there are limitations as to the number of permanent magnets used on account of expense, weight and space available. Hence it is necessary to use more windings in proportion in order to secure the desired output. If the usual inductor alternator practice of two stator teeth to one rotor tooth be followed in a small unit using permanent magnets the stator winding space will be insufficient. This difficulty has been overcome by omitting two out of every three stator teeth and increasing the cross section of the remaining teeth in order to carry the flux. For example, starting with a construction involving 24 stator teeth and 12 rotor teeth, the number of stator teeth was reduced to 8 while preserving the same frequency for a given engine speed, and resulting in three times the available winding space and approximately three times the output. This 2 to 3 ratio and the use of 12 rotor teeth has been found to give a frequency which is satisfactory from a lighting viewpoint and also for inherent external regulation by means of a resonant circuit. A two to five ratio could be employed, such as 4 stator teeth to 10 rotor teeth, but the frequency and hence the potential might be too low unless machine be operated at a higher speed. An 8 to 20 combination could be used provided the diameter of the armature is large enough to permit a rotor tooth of sufficient width to carry the flux, it being borne in mind that the rotor tooth spaces must be great enough to prevent flux leakage and the consequential inefficiency of the machine. Either combination of 8 to 12 or 8 to 20 or 4 to 10 (the 2 to 3 ratio or the 2 to 5 ratio) is possible depending on operating conditions and size. It is to be remembered that the number of rotor teeth should be divisible by half of the number of stator teeth so that the pulsations of flux from the permanent magnets will be minimized. In the combinations of stator and rotor teeth mentioned, it is apparent that there will be a line-up of rotor teeth with stator teeth for every angular movement of the rotor through angle of 360 degrees divided by twice the number of rotor teeth and the number of "line-ups" will remain constant. Since the "line-ups" come at regular intervals and are constant in number, these other advantages just mentioned will result. Of course it is necessary to minimize flux pulsations in the magnet in order that the magnetism may be retained for a long period.

By employing a double slotted armature instead of a single winding slot as in the ordinary shuttle armature the form of ignition current wave is improved and the inductance per turn of armature winding is reduced, also improving ignition.

Satisfactory ignition is provided throughout the entire range of driving speeds and

even at low speeds prevailing during cranking the engine by hand, without the use of an impulse coupling. This is accomplished by using the pole face windings to assist the armature windings during starting.

The armature circuit is established practically only as needed for ignition purposes by means of the double breaker mechanism, so that armature reaction causing a demagnetization of the permanent magnets is reduced to the minimum.

When one of the lamps 291 and 293 burns out the remaining lamp will burn with substantially the same intensity as before. Obviously more independent lamp circuits may be provided for by adding a group of pole face windings for each additional circuit.

Regulation of the lighting circuits has been accomplished without the use of moving parts.

While the head lamp circuit is called an externally regulated circuit, and the tail lamp circuit an externally unregulated circuit, it is to be understood that as to both circuits the magneto pole face windings have some inherent regulation. In the case of the windings supplying current for the tail lamp, the number of turns per pole tooth is great enough and the inductance high enough for inherent regulation. Therefore, an external regulator has not been found necessary. As the size of the machine is limited it is not practical to increase the turns per pole of the windings of the head lamp circuit to an amount sufficient for inherent regulation.

While the form of mechanism herein shown and described constitutes a preferred form of embodiment of the invention, it is to be understood that other forms might be adopted, all coming within the scope of the claims which follow.

What is claimed is as follows:

1. An electrical system comprising, in combination, a generator having a permanent magnet field and windings for generating ignition current; an ignition transformer coil; a circuit paralleling the transformer coil and including a circuit breaker; a circuit including a circuit-breaker connecting the generator windings with said coil and paralleling circuit; and engine operated means for controlling the circuit breakers in order that, at a certain time, both breakers be in circuit closing position, that the first breaker will open while the second breaker remains closed, and that the second breaker will open after the first breaker has opened, for the purpose specified.

2. An electrical system comprising, in combination, a generator having a permanent magnet field, windings for the generation of ignition current, and means for causing the generation of current in said windings and including an engine driven shaft operated at a speed twice that required for the production

- of the number of ignition current peaks necessary for ignition purposes; an ignition transformer coil; and ignition timing means including a cam on said shaft and circuit breaking devices operated by the cam for causing the following series of events only once during a revolution of the shaft: the generator windings to be connected with a short circuit and with the coil, the short circuit to be interrupted during one of the short-circuit current peaks of the generator windings, while the windings remain connected in series with the coil, and the open-circuiting of the generator windings.
- 15 3. An electrical system comprising, in combination, a generator having a permanent magnet field, windings for the generation of ignition current, and means for causing the generation of current in said windings and 20 including an engine driven shaft operated at a speed twice that required for the production

of the number of ignition current peaks necessary for ignition purposes; an ignition transformer coil; and ignition timing means including a circuit breaker located in a circuit 25 paralleling the coil, and a circuit breaker located in a circuit for connecting the generator windings with the coil and parallel circuit, and a cam on said shaft for producing the following recurrent series of operations of the 30 circuit breakers: The opening and closing of the second breaker while the first breaker is open, the opening and closing of the first breaker while the second breaker is open, the closing of the first breaker, the closing of the 35 second breaker while the first breaker is closed, the opening of the first breaker while the second breaker is closed, and the opening of the second breaker.

In testimony whereof I hereto affix my signature.

JOHN H. HUNT.
